LOCOMOTIVE FIRE-BOX

Application filed October 18, 1930. Serial No. 489,566.

Our invention relates to locomotive fire-boxes of the type adapted for burning fuel in fluid form.

The principal objects of the invention are 5 to promote fuel efficiency and minimize fuel consumption by providing for complete combustion of the fuel before entering the boiler flues, and to minimize excessive temperature strains within the fire-box, which 10 result in leaky and broken stay-bolts and leaky flues, with consequently high maintenance expense and loss of use. These objects are achieved by introducing the air and mixing it with the fuel in such a manner 15 that both are heated to combustion temperature before mixing occurs, and that thorough mechanical mixing is accomplished. Furthermore, the air is so directed that there are no relatively cold air currents 20 in the fire-box which would result in localized areas of low temperature, and said air is automatically controlled according to the power output of the engine, so that there 25 are no sudden and violent temperature fluctuations within the fire-box.

Other objects and advantages of the invention will become apparent from the following specification, which should be read with the understanding that changes, within 30 the scope of the claims hereto appended, may be made in the form, construction and arrangement of the several parts, without departing from the spirit of the invention as set forth in said claims.

35 A preferred embodiment of our invention will now be fully described with reference to the accompanying drawing, wherein:—

Fig. 1 is a longitudinal central section of our fire-box and the rear portion of a locomotive boiler.

Fig. 2 is a transverse section taken on the line 2—2 of Fig. 1.

In the drawing, the reference numeral 3 designates the rear portion of a locomotive 45 boiler of usual construction, having flues 4. The fire-box 5 is also mainly constructed according to usual practice, having crown sheet 6, rear wall 7 with fire-door 8, front wall or flue sheet 9, side walls 10, fire pan 11 with fire brick lining 12, and fire-brick flash

wall 13. A burner 14, adapted to inject a jet of oil or other fuel in fluid form into the fire-box, is positioned in the front wall of the fire-pan 11. The path of the fuel stream into and through the fire-box is indicated 55 by the arrows 15 in Fig. 1. An air opening 16, of limited area, is provided around the burner 14. This opening is of such size that only enough air enters through it to prevent over heating of the burner tip, and to start 60 combustion of the fuel stream 15. So much is usual locomotive construction.

At the rear of the fire-pan 11, just forward of the flash wall 13, we provide three air inlet openings. One, shown at 17, is 65 in the longitudinal center of the fire-pan, and is controlled by a damper 18, which has a lever 19 adapted to be connected with any suitable manual operating means, not shown, within the control of the fireman. A shield 70 or chute 20 below the aperture 17 prevents sparks and pieces of hot brick from dropping to the road bed beneath.

The other two air inlet openings 21 are 75 symmetrically positioned on the two sides of the inlet 17, and have interior flanges 22 to retain the brick-work and to direct the entering streams of air angularly upward, as indicated by the arrows 23 in Fig. 2, so that said air streams meet at a point 24 in 80 front of the flash wall 13 and directly above the horizontal line of the incoming fuel stream 15.

The air inlets 21 have exterior chutes 25 to prevent the dropping of sparks and hot 85 pieces of brick, and are controlled by automatic or draft-operated flap dampers 26. These latter are positioned in the open upper sides of the chutes 25, to prevent clogging 90 from pieces of brick which may drop into said chutes, and are pivotally mounted at 27 and normally held closed by weights 28 adjustably secured upon arms 29. The weights 28 are so adjusted that the dampers 26 will remain closed under natural draft 95 conditions in the fire-box, i. e. when the engine is not working, but will open when forced draft occurs, due to the engine exhaust, as shown by the broken line position 100 at the right of Fig. 2.

In the operation of a locomotive having our improved fire-box, sufficient air enters through the opening 16 around the burner to start combustion of the fuel, and by the 5 time the fuel stream has traveled from the burner to the flash wall, its temperature has been raised by this partial combustion to a point at which complete combustion will occur upon the admission of sufficient additional air.

In firing up the boiler, and when the engine is drifting, i. e. when only a light fire is required, the necessary additional air is admitted through the central or auxiliary 15 inlet 17 by opening the manually controlled damper 18. Under these conditions, there being no forced draft, the automatic dampers 26, controlling the side or main air inlets 21, remain closed. When the engine is 20 working, however, and its exhaust sets up a forced draft in the fire-box, the automatic dampers 26 open, admitting a relatively large quantity of additional air, which rises in two converging streams across the face 25 of the hot flash wall 13, thereby becoming heated, and intersects and mixes with the rising fuel stream at the point 24, at which point complete combustion occurs.

When the engine throttle is closed, the 30 forced draft ceases, and the automatic dampers 26 immediately close, thereby preventing an excessive amount of air from entering and cooling the fire-box. Thus violent changes in temperature are prevented.

35 The manually controlled auxiliary air damper 18 may be open or closed when the engine is working, depending on whether or not sufficient air enters through the main automatic dampers 26. It is intended that 40 sufficient air will enter through said main dampers for ordinary working conditions, so that the auxiliary damper 18 will normally be closed, and need only be opened under conditions of unusual load, and also, 45 as before stated, under conditions of no load, when the main dampers are closed and a light fire is to be maintained.

It is to be noted that, with the exception 50 of the small amount of air entering at 16 around the burner, and which is immediately heated and used by the partial combustion of the fuel stream, all the entering air passes over the face of the hot flash wall 13, and is thereby heated before mixing 55 with the fuel, so that there are no cold drafts within the fire-box, nor is said fuel cooled below the temperature necessary to complete combustion. Furthermore, the intersecting from different directions, of the two main 60 air streams 23 with the rising fuel stream, causes very complete mechanical mixing of air and fuel, and this, together with the maintenance of high temperatures of both air and fuel, enables satisfactory combustion 65 to occur at or near the point 24, and to be

entirely completed before the gases enter the boiler flues. There is, therefore, no deposition of soot or carbon, and no waste of fuel.

Thus our invention, by preventing unequal temperatures and violent temperature changes within the fire-box, reduces maintenance costs and loss of use; and by insuring complete combustion, prevents waste of fuel and further reduces maintenance costs ordinarily caused by the necessity of cleaning soot out of the fire-box and boiler flues.

We claim:

1. In a fire-box having a flash wall at one end and a pair of laterally spaced air inlets in its lower portion adjacent the face of said flash wall, a burner adapted to direct a stream of fuel substantially horizontally against the lower central portion of said flash wall, said fuel stream then rising along the face thereof, means for directing the air streams entering through said inlets upwardly over the face of said flash wall and convergingly to a common intersection with the rising fuel stream; and automatic dampers responsive to draft conditions in the fire-box for controlling said air inlets.

2. In a fire-box having a flash wall and a plurality of air inlets in its lower portion adapted to direct intersecting streams of air upwardly over the face of said flash wall, a burner adapted to direct a stream of fuel against said flash wall, said fuel stream then rising along the face thereof and intersecting said air streams, a manually operated damper for controlling one of said air streams; and an automatic damper responsive to draft conditions in the fire-box for controlling another of said air streams.

3. In a fire-box having a flash wall and three laterally spaced air inlets in its lower portion adapted to direct intersecting streams of air upwardly over the face of said flash wall, a burner adapted to direct a stream of fuel against said flash wall, said fuel stream then rising along the face thereof and intersecting said air streams, a manually operated damper for controlling the central air inlet; and automatic dampers responsive to draft conditions in the fire-box for controlling the side air inlets.

In testimony whereof we have signed our names to this specification.

GEORGE L. BAXTER.
